UNITED STATES PATENT OFFICE

GUSTAV B. PETSCHE, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

BLOWING-ENGINE.

No. 899,558.

Specification of Letters Patent.

Patented Sept. 29, 1908.

Application filed October 17, 1907. Serial No. 397,818.

To all whom it may concern:

Be it known that I, GUSTAV B. PETSCHE, a subject of the Emperor of Germany, residing in the city and county of Philadelphia, in the 5 State of Pennsylvania, have invented a certain new and useful Improvement in Blowing-Engines, of which the following is a true and exact description, reference being had to the accompanying drawings, which form a 10 part thereof.

The present invention relates to blowing engines or air compressors, and particularly to the means for actuating the inlet or suction valves of such engines.

15 The primary object of the invention is to provide a connection between each inlet valve and the valve gear proper so that the inlet valve will if closed be moved positively into the open position at the proper period in

20 the stroke of the reciprocating piston, while at the same time providing a suitable yielding connection, such as is formed by a piston and vacuum cylinder, between the valve and the valve gear which tends to close the inlet

25 valve during the compressing stroke of the compressing piston, and also providing means controlled manually or automatically or in both ways for releasably holding the inlet valve in the open position. With these

30 provisions the inlet valve may be released from its holding means and moved into the closed position at a definite period in the stroke of the compressing piston for normal operation, or may be delayed in closing

35 where it is desired to compress less than the normal amount of air, or may be held open throughout the compressing stroke to reduce the load on the engine when for any reason no compression is required, as because the

40 receiver pressure is high enough or to facilitate the starting of the engine, the latter being of particular importance when the driving engine is a gas engine or the like which does not start with readiness under load.

45 The various features of novelty which characterize the invention are pointed out with particularity in the claims annexed to and forming a part of this specification. For a better understanding of this invention,

50 however, and the advantages possessed by it, reference may be had to the accompanying drawings and descriptive matter in which I have illustrated and described forms in which the invention may be embodied.

Of the drawings, Figure 1 is an elevation of 55 a blowing engine equipped with one form of my invention. Fig. 2 is an elevation taken at right angles to Fig. 1, with a portion of the mechanism shown in section. Fig. 3 is a sectional elevation taken on the line 3—3 of Fig. 1, but on a larger scale than Figs. 1 and 2, and showing a portion only of the mechanism. Fig. 4 is a view similar to Fig. 3, showing a modified construction. Fig. 5 is a partial sectional elevation taken on the line 5—5 60 of Fig. 4, but on a larger scale. Fig. 6 is a sectional elevation taken on the line 6—6 of Fig. 5. Fig. 7 is a somewhat diagrammatic representation of the engine taken generally similar to Fig. 1, and showing a further modification of the invention, and Fig. 8 is a perspective view showing in detail the construction of Fig. 7.

In the drawings, and referring at first particularly to Figs. 1, 2, and 3, the blowing engine shown is of a well known type, such as is shown and described in my Patent No. 784,122, granted March 7, 1905. A represents the double action compressing cylinder having receiver connections A' at 75 each end, and having also air inlet ports A² at each end. At each end of the cylinder are located an inlet valve and a delivery valve, but as the particular construction of these valves is well known and forms no part of the 80 present invention, it is not thought necessary to illustrate them or describe them herein further than to say that they may be of the gridiron type as shown in my said prior patent, and that each delivery valve has a stem 85 B, and each inlet valve a stem C, which extend into the corresponding casing B' and C'.

The valve gear for operating both the inlet and outlet valves of the compressor comprise, in the form shown, a shaft D, which is 90 rotated through gearing located in a housing A¹ in definite relation to the to and fro strokes of the piston rod A³ secured to the compressing piston in cylinder A. The shaft 95 D carries eccentrics D' pertaining to the admission valve, and eccentrics D² pertaining to the outlet valves. The eccentrics D' and D² oscillate rock shafts D⁵ and D⁶ through suitable connecting rods D³ and D⁴ and arms 100 from the latter.

105 The means by which each delivery valve is operated from the rock shaft D⁶ comprises a piston B³ connected to crank arms D⁷ of the

rock shaft D⁶ by a rod D⁸. The piston B³ slides in a chamber B⁵ formed to receive it in a piston head B² secured to the end of the valve stem or valve operating rod B, and 5 sliding in a chamber B⁴ formed in the casing B'. The delivery valve opens when the stem B moves outward in the direction of the arrow shown in Fig. 2. The valve is opened when the receiver pressure reaches 10 the proper point by air admitted to the inner side of the piston B⁴ from the compressing cylinder through the connection B⁶ running from the compressing cylinder to the piston chamber B⁴. The piston B³ is at this time. 15 moved out of the position shown in Fig. 2 by the oscillation of the shaft B⁶ so as not to interfere with the opening of the valve. The piston B³ serves to close the valve at the proper point, and also as a means for trapping 20 air in the chamber B⁵ in which it plays to thereby cushion the opening movement of the delivery valve. Suitable means may be employed for regulating this cushioning action, as by regulating the leakage between 25 the piston B³ and the wall of the chamber B⁵. No claims on the delivery valve operating mechanism are made herein as this mechanism is described and claimed in my prior application Serial No. 2,309, filed January 30 22, 1900.

Each rock shaft D⁶ has secured to it crank arms D⁹ connected by a rod D¹⁰ to a piston C³ which works in the piston chamber C⁵ formed in the piston C² secured to the outer 35 end of the corresponding inlet valve stem or operating rod C. The piston C² works in the vacuum piston chamber C⁴ formed in the casing C'. Admission of air from the atmosphere to the inner end of the piston chamber 40 C⁴ is controlled by a rotary valve F, which may be moved to open or close to the atmosphere the outer end of the port F' which communicates with the casing port C⁶ running to the inner end of the chamber C⁴. The es- 45 cape of air from the chamber C⁴ when the piston C² moves toward its inner end is permitted by the non-return or check valve C⁷. The valve closing movement of the piston C² is cushioned by air trapped in the chamber 50 C⁸ at the front end of the piston, which may be regulated by the size of the restricted opening C⁹. The outward movement is also checked to some extent by the slight leakage in the chamber C⁵ which occurs in practice. 55 The valves F may be alternately opened and closed in regular succession by suitable connections from the shaft D. These connections, shown best in Fig. 3, include an eccentric D¹¹, a connecting rod D¹², a lever G, to the 60 outer end of which the rod D¹² is pivotally connected, a link F³ connecting the inner end of the lever G and the outer end of an arm F² secured to the rotary valve F, and a movable fulcrum pin G' for the lever G. In the form 65 shown, the fulcrum pins G' for the two levers

G at opposite ends of the engines are carried by arms G² projecting from a rock shaft G³, which has secured to it another arm G⁴ carrying at its outer end a gear segment G⁵. The gear segment G⁵ meshes with a worm 70 wheel H which can be rotated through a hand wheel H'. An indicator finger G⁶ and co-operating dial show the position of the fulcrum pin.

It will be understood that each eccentric 75 D' is so set and the connections between it and the corresponding rock shaft D⁶ and between the latter and the piston C³ connected to it are so arranged to cause the piston C³ to move in and begin to open the admission valve connected with it, if the latter is closed, as soon as the corresponding suction stroke begins. The positive opening of the valve is preferably completed comparatively early in the suction stroke. After the inward 80 movement of each piston C³ is completed, the latter moves outward and is maintained at a distance away from the inner limit of its stroke equal to or exceeding the outward movement of the piston C², throughout the 85 following compression stroke, so that at any point in this stroke the corresponding admission valve may, if released, open to its full extent under the action of the vacuum maintained in the chamber C⁵. The move- 90 ment of the piston C³ is for convenience made greater than the movement of the piston C². 95

Until air is admitted to the inner end of a chamber C⁴ this chamber and its piston C² unite to form a lock holding the corresponding admission valve in the open position. Whenever air is admitted to the front end of a chamber C⁴ by its valve F, the pressure of the air against the large front end of the piston C² closes the attached admission 100 valve, since the pressure of the atmosphere has been taken off of a large portion of the outer end of the piston C² by the piston C³.

In normal operation each valve F is opened 105 through its operating connection from the shaft D at the beginning of the corresponding compression stroke. When it is desired for any reason to delay the point at which a valve F opens in order to delay the closing of the corresponding admission valve and thereby reduce the amount of air compressed at that stroke of the compressing piston, the corresponding hand wheel H' is rotated to properly adjust the fulcrum pin G' and thereby change the throw of the lever G. By displacing the fulcrum pin G' far enough the corresponding admission valve 110 can be prevented from closing at all, thus preventing any compression from taking place in the corresponding end of the compressing cylinder.

Instead of the arrangement for varying 115 the operation of the valve F shown in Figs. 1, 2, and 3, the arrangement shown in Figs. 4, 5, and 6 may be employed. In this modi- 120

fied form of the invention the connecting rod D¹² is connected directly to the valve arm F². In this form, however, the valve seat F⁴ for the valve F is made angularly adjustable, 5 and has secured to it an operating arm F⁵ carrying a gear segment F⁶ which meshes with a spur gear F⁷ carried by a shaft F⁸ which may be oscillated by the hand wheel F⁹. The shaft F⁸, which runs between the 10 two valves F at the opposite ends of the cylinder, may be locked in any position into which it may be turned by the set screw F¹⁰. By rotating the valve seat F⁴, and thereby angularly adjusting its port F¹¹, the point in 15 the strokes of the compressing piston at which the ports F¹² of the valves F register with the ports F¹¹ and thereby admit air to the cylinders C¹ may be varied as desired.

Figs. 7 and 8 illustrate an arrangement in 20 which the valves F are automatically maintained in the closed position, and the admission valves are consequently maintained in the open position whenever the receiver pressure rises above a predetermined value. 25 In this construction, the shaft F⁸ of Figs. 4 and 5 has secured to it an arm F¹³, which is connected by the jointed rod I to a piston I' working in a cylinder I². The lower end of the piston chamber is connected to one of 30 the receiver casings A' by a conduit I³, and a spring I⁴ is placed between the upper end of the piston and the upper wall of the piston chamber, the spring being so proportioned that as the receiver pressure rises above a 35 predetermined value the piston will be raised and the shaft F⁸ will be rotated to adjust the ports F¹¹ and thereby reduce or entirely prevent compression from occurring in the compression cylinder. A hand lever I⁵ forms a 40 means in this construction by which the adjustment may be made manually.

The constructions described possess a 45 number of important operating advantages. For one thing, the various valves are properly cushioned. The importance of this is obvious when it is considered that the inlet and outlet valves are massive and may exceed one thousand pounds each in weight in the larger size engines, and these valves are 50 required to move very rapidly from the open to the closed positions to prevent wire drawing. The piston and vacuum cylinder connection for producing the outward pull on the inlet valves to move the latter when released possesses the advantages that the 55 parts are subject to little wear and are not injured in operation, as would be the case for instance if spring connections were employed. By employing the pressure of the 60 atmosphere to move the inlet valves to the closed position a definite and powerful moving force is obtained which may be controlled in an easy and effective manner.

Having now described my invention, what

I claim as new and desire to secure by Letters Patent is:

1. In a blowing engine having a compression chamber and an inlet and an outlet valve therefor, means for moving the inlet valve arranged to positively open the valve, if closed, at the beginning of each suction stroke in the compression chamber and tending to close the inlet valve throughout the following compression stroke, and means independent of the valve moving means for releasably holding the inlet valve in the open position.

2. In a blowing engine having a compression chamber and an inlet and an outlet valve therefor, means for moving the inlet valve arranged to positively open the valve, if closed, at the beginning of each suction stroke in the compression chamber, and tending to close the inlet valve throughout the following compression stroke, and means responsive to the pressure of the fluid compressed and independent of the valve moving means for releasably holding the inlet valve in the open position.

3. In a blowing engine having a compression chamber, an inlet and outlet valve therefor, a shaft rotating in definite relation to the speed of the engine and connections therefrom for moving the inlet valve, arranged to positively open the inlet valve, if closed, at the beginning of each suction stroke in the compression chamber and tending to close the inlet valve throughout the following compression stroke, valve controlled means for holding the inlet valve in the open position, a controlling valve for said means, and a connection from said shaft for opening and closing said controlling valve.

4. In a blowing engine having a compression chamber, an inlet and outlet valve therefor, a shaft rotating in definite relation to the speed of the engine and connections therefrom for moving the inlet valve, arranged to positively open the inlet valve, if closed, at the beginning of each suction stroke in the compression chamber and tending to close the inlet valve throughout the following compression stroke, valve controlled means for holding the inlet valve in the open position, a controlling valve for said means, a connection from said shaft for opening and closing said controlling valve, and means for adjusting the last mentioned means to regulate the time of closing the inlet valve.

5. In a blowing engine having a compression chamber and outlet and inlet valves for said chamber, operating means for the inlet valve comprising a pair of members, one movable with the inlet valve and the other independently thereof, means for giving said other member a to and fro movement in definite relation to the engine movement, a yielding connection between said members tend-

ing to close the inlet valve during the compression stroke in the compression chamber, said connection comprising a piston carried by one of said members which enters the 5 open end of a piston chamber formed in the other member and open at one end only, and means releasably holding the inlet valve in the open position.

6. In a blowing engine having a compression chamber and an inlet and outlet valve therefor, a member connected to the inlet valve and formed with a piston chamber C⁵, a piston C³ fitted in said piston chamber, means for moving said piston C³ in definite 10 relation to the speed of the engine and so that it engages said member to move the valve, if closed, into the open position at the beginning of each suction stroke and is maintained during the compression stroke away 15 from the member when the latter is in the closed position a distance equal to or exceeding the opening movement, whereby a vacuum is then maintained in said chamber so long as the valve remains open tending to 20 move the valve into the closed position, and means for releasably holding the valve in the open position.

7. In a blowing engine having a compression chamber and an inlet and an outlet valve 30 therefor, a casing C' having a piston chamber C⁴, a piston C² movable in said chamber and connected to the inlet valve and having a piston chamber C⁵ formed in it, a piston C³ fitted in said chamber C⁵, means for moving 35 said piston C³ in definite relation to the speed of the engine and arranged to engage the piston C² and open the valve, if closed, at the beginning of the suction stroke, and to maintain a vacuum in said chamber C⁵ tending to 40 close the valve during such portion of the compression stroke as the valve remains open, and means for releasably holding the piston C² in the valve open position, said 45 means comprising a valve controlling the admission of air to the chamber C⁴.

8. In a blowing engine having a compression chamber and an inlet and an outlet valve therefor, a casing C' having a piston chamber C⁴, a piston C² movable in said chamber and 50 connected to the inlet valve and having a piston chamber C⁵ formed in it, a piston C³ fitted in said chamber C⁵, means for moving said piston C³ in definite relation to the speed of the engine and arranged to engage the piston C² and open the inlet valve, if closed, at 55 the beginning of the suction stroke, and to maintain a vacuum in said chamber C⁵ tending to close the inlet valve during such portion of the compression stroke as the inlet 60 valve remains open, means for releasably holding the piston C² in the valve open position, comprising a valve controlling the ad-

mission of air to the chamber C⁴, and connections for opening and closing said controlling valve in definite relation to the speed of the 65 engine.

9. In a blowing engine having a compression chamber and an inlet and an outlet valve therefor, a casing C' having a piston chamber C⁴, a piston C² movable in said chamber and 70 connected to the inlet valve and having a piston chamber C⁵ formed in it, a piston C³ fitted in said chamber C⁵, means for moving said piston C³ in definite relation to the speed of the engine and arranged to engage the piston C² and open the inlet valve, if closed, at 75 the beginning of the suction stroke, and to maintain a vacuum in said chamber C⁵ tending to close the inlet valve during such portion of the compression stroke as the inlet 80 valve remains open, mechanism controlling the admission of air at the proper time to the chamber C⁴ to permit the inlet valve to close, comprising a hollow rotary valve member F provided with a valve port F¹² and an angularly adjustable valve seat member F⁴ provided with the port F¹¹, means for oscillating the valve F in definite relation to the movement of the engine speed, and means for adjusting the valve seat member F⁴ to adjust 85 the time in which the ports are brought into register.

10. In a blowing engine having a compression member and an inlet and an outlet valve therefor, a casing C' having a piston chamber 95 C⁴, a piston C² movable in said chamber and connected to the inlet valve and having a piston chamber C⁵ formed in it, a piston C³ fitted in said chamber C⁵, means for moving said piston C³ in definite relation to the speed 100 of the engine and arranged to engage the piston C² and open the inlet valve, if closed, at the beginning of the suction stroke, and to maintain a vacuum in said chamber C⁵ tending to close the inlet valve during such portion 105 of the compression stroke as the inlet valve remains open, mechanism controlling the admission of air at the proper time to the chamber C⁴ to permit the inlet valve to close, comprising a hollow oscillatory valve member F provided with a valve port F¹² and an angularly adjustable valve seat member F⁴ provided with the port F¹¹, means for controlling the valve F in definite relation to the movement of the engine speed, and means for adjusting the valve seat member F⁴ to adjust 110 the time in which the ports are brought into register in response to the pressure of the receiver into which the blowing engine 115 discharges.
